DESIGN FOR A CONFECTION

Edward L. Schoettle, Cincinnati, Ohio, assignor to
The John Mueller Licorice Company, Cincinnati,
Ohio, a corporation of Ohio

Application May 9, 1941, Serial No. 100,881

Term of patent 7 years

To all whom it may concern:

Be it known that I, Edward L. Schoettle, a citizen of the United States of America and a resident of Cincinnati, in the county of Hamilton and State of Ohio, have invented a new, original, and ornamental Design for a Confection, of which the following is a specification, reference being made to the accompanying drawing, forming a part thereof.

Fig. 1 is a top plan view of the confection showing my new design.

Fig. 2 is a side elevational view of the confection.

Fig. 3 is a cross-sectional view taken on line 3—3 of Fig. 2.

Fig. 4 is a front elevational view of the confection.

I claim:

The ornamental design for a confection, as shown.

EDWARD L. SCHOETTLE.
